(57) **CLAIM**

The ornamental design for a lid as shown and described.

DESCRIPTION

FIG. 1 is a bottom, front, and right-side perspective view of a lid showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a detail view, as annotated in FIG. 1;

FIG. 9 is a detail view, as annotated in FIG. 6;

FIG. 10 is a detail view, as annotated in FIG. 6;

FIG. 11 is a detail view, as annotated in FIG. 7;

FIG. 12 is a cross-sectional view, taken in the direction of line 12-12 in FIG. 6;

FIG. 13 is a detail view, as annotated in FIG. 12;

FIG. 14 is a cross-sectional view of the lid of FIG. 12, shown in a state of environmental use; and,

FIG. 15 is a cross-sectional view of the lid of FIG. 12, shown in another state of environmental use.

The evenly dashed broken lines illustrating a second lid in FIG. 14 and a cup in FIG. 15 represent environmental structure. All other evenly dashed broken lines represent portions of the lid. The dot-dashed broken lines in FIGS. 1-8 and 10-15 represent the bounds of the claim. The dot-dot-dashed broken lines represent detail views. The broken lines form no part of the claim.
